DEVICE FOR GRIPPING AND HOLDING A
WEFT THREAD IN NIPPER LOOMS

Albert Moessinger, Winterthur, Switzerland, assignor to Sulzer Freres, Societe Anonyme, Winterthur, Switzerland

Application October 1, 1945, Serial No. 619,522
In Switzerland August 15, 1945

15 Claims. (Cl. 139—126)

1

The present invention relates to a device for gripping and holding a weft thread in nipper looms after insertion of the thread into the shed and before the beating up into the fabric. The invention consists in that the thread gripper is fixed movably on its operating member and held in its normal working position by yielding means.

As is known, looms with free flying shuttles are provided with a control device for the flight of the shuttle, which comes into operation and causes the loom to come to rest if the shuttle fails to enter the shuttle box at all or at the right time. In such cases this stopping of the loom at the right time prevents the occurrence of one or more beats by the reed, which would lead to damage being done to the reed, the warp threads or the fabric.

In nipper looms with weft bobbins arranged outside the shed, the weft thread is held during the beat of the reed in known manner by edge thread grippers which must previously move into the path of the shuttle in order to grip the weft thread; there is therefore always a risk of the edge thread gripper colliding with a shuttle moving late towards the shuttle box, with the result that these parts may be damaged. In order to diminish this risk, the moving forward of the edge thread gripper into the path of the shuttle has hitherto been set to occur later than the latest permissible entrance of the shuttle into its shuttle box. But since on the one hand a certain time must elapse between the moment when the control device comes into operation and the time when the loom is completely at rest, in consequence of the inertia forces of the considerable masses which are in motion, but on the other hand this movement must have stopped by the time the edge thread gripper has come into the path of the shuttle, i. e. into its gripping position, there is necessarily a disadvantageous shortening of the time available for the flight of the shuttle within one pick.

With the device according to the invention a shortening of the time available for the flight of the shuttle is avoided and damage to the parts of this device in consequence of collision with the shuttle is prevented. As a result the output of a loom equipped with the device according to the invention is increased.

By way of example forms of execution of the subject matter of the invention are illustrated diagrammatically in the accompanying drawing, where:

Fig. 1 shows the view of a whole loom, seen from the cloth beam side.

2

Figs. 2 and 3 show a first example of execution in side elevation and plan respectively, with the gripper control removed,

Fig. 4 the same example of execution with the thread gripper swung out of the normal position,

Figs. 5 and 6 a second example of execution in side elevation and front view respectively,

Fig. 7 a further example of execution in side elevation, and

Fig. 8 the same with thread gripper swung out of the normal position.

The loom illustrated diagrammatically in Fig. 1 has two side frames 1, 2, between which are arranged the cloth beam 3 with the wound-on fabric 5, the reed 28 and the heald shafts 30. Near the inner sides of the frames 1 and 2 a device 4 is provided at each side to grip and hold the weft thread 6, which is wound on a weft bobbin 7 located outside the shed, for instance on the side frame 1. The weft thread may consist of vegetable, animal or mineral material. By means of a shuttle 8 moving along the shuttle path 9 the weft thread 6 is led through the shed, the shuttle 8 arriving in the shuttle box 10 which is arranged in the side frame 2. The control device 11 supervises the entrance of the shuttle 8 into the shuttle box 10, causing the loom to be stopped in time, in case the entrance of the shuttle should be delayed or not take place at all. After the weft thread 6 has been inserted into the shed the devices 4 move into the path 9 of the shuttle 8 in order to hold the thread 6 while it is being beaten up by the reed 28 into the fabric 5. Instead of arranging a device 4 on the side frame 1 and a device 4 on the shuttle box 10, only the one on the shuttle box 10 could be provided as being the more important. When dividing the fabric into several lengths, such a device could be arranged also between each two adjacent fabric lengths.

In the example shown in Figs. 2 to 4 the device for gripping and holding the weft thread has a thread gripper which is equipped with two arms 12, 13 approximately at right angles to each other. The thread gripper 12, 13 is fixed to the operating bar 15 by means of the bearing pin 14. The arm 13 is provided with a notch 16 and at its end with a stop pin 21. Through the notch 16 the spring-holding bolt 18 is fixed to the operating bar 15. On the bolt 18 is fixed the torsion spring 19, one end of which presses on the pin 21 and thus keeps the thread gripper 12, 13 in its normal working position, which is determined by the stop between notch 16 and bolt 18 and is

transversely directed to the operating bar 15. The end of the thread gripper arm 12 is constructed as gripper cheek 20. Through this and through the arm 13 the guide pin 17 of the gripper cheek 22 is passed, being movable in the direction of its length. To the pin 17 a spring plate 23 is fixed. Between this and the gripper cheek 20 a compression spring 24, through which the pin 17 passes, is inserted; this spring presses the pin 17 on to a cam 25. The cam 25 is fixed to the operating bar 27 by screws 26 by means of which it can be adjusted.

In the left part of Fig. 2, the thread gripper 12, 13 is shown in its gripping position, in which it is in the path 9 of the shuttle 8. In order to be able to grip the weft thread 6, the guide pin 17 is pressed downwards by the cam 25 and the gripping cheeks 20, 22 consequently open, so that the weft thread 6 comes between the gripper cheeks when the gripper is advanced. While the thread gripper 12, 13 with its two gripper cheeks 20, 22 is in its outermost position, and lying in the path 9 of the shuttle, the operating bar 27 with the cam 25 moves in the direction of the arrow 35, so that the cheeks 20, 22 close under the action of the spring 24 and hold the weft thread 6 firmly. While the reed 28 beats the weft thread 6 into the fabric, the operating bar 15 with the thread gripper 12, 13 simultaneously moves in the direction of the arrow 36 into its right hand end position and holds the weft thread 6 firmly so that it keeps the tension received when being inserted.

Now follows the change of shed formed by the warp threads 29. This is effected by moving the heald shafts 30. These movements are executed in accordance with the type of fabric 5 to be manufactured. On the shaft 30 are fixed the healds 31 with the eyes 32. The weft threads 29 are led through the eyes 32 and must therefore follow the movement of the shafts 30.

The ends of the weft thread 6 last beaten up into the fabric 5, are held by the gripper cheeks 20, 22 (Fig. 3) until the beginning of the next gripping phase. Shortly before the beginning of this phase, the operating bar 27 moves in the direction of the arrow 36, so that the gripper cheeks 20, 22 open. With the operating bar 15, the operating bar 27 moves simultaneously in the direction of the arrow 35, so that the gripper cheeks 20, 22 are brought into the gripping position while they are open.

If the shuttle 8 moves late towards the shuttle box 10, it may happen, as shown in Fig. 4, that the thread gripper 12, 13 and particularly its parts 20, 22, knock against the shuttle 8. The gripper cheeks 20, 22 are thus held back, while the operating bar 15 must positively move still further in the direction of the arrow 35 until it comes into its left end position (Fig. 2), since the loom is still in action. The thread gripper 12, 13 then swings on the pin 14 counter-clockwise, so that its arm 13 moves upwards and gives tension to the torsion spring 19. Since the shuttle 8 has not arrived at the proper time in the shuttle box 10, the control device 11 (Fig. 1) comes into operation and brings the loom to rest before the reed 28 begins its working movement. In spite of the fact that the control device (Fig. 1) comes into operation, not when the shuttle 8 passes at the proper time in front of the gripper cheeks 20, 22 advancing into the shuttle path 9, but when the shuttle 8 arrives late in the shuttle box 10, and consequently comes into operation first at a later point of time, the operating bar 15 can carry out

its motion to the end in the direction of the arrow 35. Since the thread gripper 12, 13 is movably fixed on the operating bar 15, the collision between the shuttle 8 and the gripper cheeks 20, 22 cannot lead to any damage being done to these parts, since the thread gripper 12, 13 swings out elastically.

In the example of execution shown in Figs. 5 and 6, the operating bar 37 is equipped with an angular arm 38, which is provided with a stop 39. By means of the bolt 40, the thread gripper 41 is fixed rotatably to the operating rod 37. On the bolt 40, a torsion spring 42 is arranged, whose extended end lies on the gripper 41 and presses it against the stop 39 into the normal working position, which is directed transversely to the operating bar 37. This torsion spring 42 is chosen so strong, that it overcomes the inertia forces of the thread gripper 41 caused by the motion of the operating bar 37; the gripper can swing in counter-clockwise direction and the torsion spring 42 holds it firmly on the stop 39. Through the gripper cheek 43 and the short arm 45 is passed the pin 47 of the counter cheek 44. By means of the compression spring 46, arranged in the same way as in the example of execution shown in Figs. 2 to 4, and by means of the cam 25 fixed to the operating bar 27, the pin 47 causes the opening and closing of the gripper cheeks 43, 44 and thus frees the weft thread 6 or holds it respectively. The advantage of this thread gripper 41 consists particularly in the shortness of the arm 45, whereby a reduction is obtained in the gripping masses which are swung. If a collision occurs with the thread gripper 41 advancing into the shuttle path 9, because of the late arrival of the shuttle 8 into the shuttle box 10, this will produce only small forces of acceleration, since the mass of the thread gripper 41 set into swinging motion is small, so that the sensitive gripper cheeks 43, 44 can be to a great extent protected from damage.

Corresponding to the example of execution shown in Figs. 7 and 8, on the foot 50 of the thread gripper 49 a gripper cheek 51, formed as a two-armed lever, is hinged by means of the pin 52 fixed on the foot 50. The gripper cheek 51 is pressed against the foot 50 by a compression spring 53 supported by a spur on the thread gripper 49. The thread gripper 49 is hinged to the operating bar 55 by means of a pin 54. The operating bar 55 is provided with an arm 56 to which the tension spring 57 is attached, the other end of which is fixed to the lever arm 58 of the thread gripper 49, so that the contact surface 59 of the lever arm 58 is pressed against the contact surface 60 of the arm 56. The operating bar 55 is carried in a guide 61 in such a way that it moves essentially in the direction of its axis 62. The amount of movement of which the operating bar is capable lies between the two extreme positions of the pin 54 shown in full and dotted lines. The shuttle 8 entering into the shuttle box 10 has inserted the weft thread 6 into the shed.

For opening and closing the thread gripper 49, the gripper cheek 51 is actuated by means of the arm 63 of a bell crank lever, so that the control surface 64 of this arm presses against the cam 65 on the cheek 51. The bell crank lever is pivotably supported on a pin 66 fixed to the side frame 1 or 2 (Fig. 1) and coupled by a second arm 67 to an operating bar 68, which is set in oscillating motion in the directions of the arms 69, 70, by means of mechanism not shown.

The length of the control surface 64 is chosen in such a way that the cam 65 remains within the range of this surface 64 in spite of its oscillating motion in the directions of the arrow 69, 70 caused by the operating bar 55.

In the normal service the method of working of the device illustrated in Fig. 7 is as follows: The operating bar 55 and the thread gripper 49 jointed to it and held in the normal working position, make an oscillating motion in the directions of the arrows 69, 70. The tension spring 57 is however chosen stronger than the inertia forces acting on it, so that the contact surfaces 59, 60 are not separated from each other because of these movements. The amount of movement of the operating bar 55 and of the bar 68 in the directions of the arrows 69, 70, are chosen to suit each other and are positively connected to each other.

The left part of Fig. 7 shows the thread gripper 49 in its gripping position in which the weft thread 6 lies between the opened gripper cheeks 50, 51, since the control surface 64 is still in its upper end position. Now the operating bar 68 moves in the direction of the arrow 70, so that the spring 53 expands, the gripper cheeks 50, 51 close and the weft thread 6 is held firmly. After the thread gripper 49 has been closed in this manner, the operating bar 55 makes a motion in the direction of the arrow 70 and brings the closed thread gripper 49 together with the weft thread 6 into the right hand end position shown in Fig. 7. This motion occurs approximately simultaneously with the beating up of the weft thread 6 into the fabric 5 by means of the reed 28 (see Figs. 1 and 3). After the shed has been changed and after a new weft thread 6 has been inserted into the shed, the operating bar 68 moves in the direction of the arrow 69 and opens the gripper 51. The gripper cheeks 50, 51 release the ends of the weft thread 6 beaten up in the fabric, and the operating bar 55 leads the thread gripper 49 in the direction of the arrow 69 again into the gripping position.

Now, if it should happen that the shuttle 8 for some reason or other does not arrive in the shuttle box 10 at all, or at the right time, and is in the path of motion of the grippers 50, 51, the thread gripper 49 or its parts 50, 51 will knock against the shuttle 8 as shown in Fig. 8, whilst the operating bar 55 continues its motion in the direction of the arrow 69 until it reaches its left hand end position. The thread gripper 49 turns on the pin 54 in counter-clockwise direction, so that the spring 57 is given tension. Because of the thread gripper 49 being movably fixed to the operating bar 55, the collision between the shuttle 8 and the gripper cheek 50 cannot cause any damage to these parts. Since the shuttle 8 does not enter its shuttle box 10, the control device 11 (Fig. 1) comes into operation and the loom is consequently stopped. After removing the cause of disturbance, the loom can be restarted, since the thread gripper 49 is automatically brought back again by means of the tension spring 57 into its normal working position with respect to the operating bar 35.

I claim:

1. A thread gripper for looms, comprising a lever member having a clamping arm, a reciprocatingly movable operating member having an end portion swingably connected to said lever member, resilient means connected with said operating member and engaging said lever member and forcing it into operating position, the

direction of movement of said operating member being substantially at a right angle to said clamping arm.

2. A thread gripper for looms, comprising a lever member having a clamping arm, a reciprocatingly movable operating member having an end portion pivoted to said lever member and its pivot point forming the fulcrum of said lever member, resilient means connected with said operating member and engaging said lever member and forcing it into operating position, said clamping arm when in normal operating position, extending substantially at a right angle to the direction of movement of said operating member.

3. A thread gripper for looms comprising a lever member having a clamping arm and an extension, a substantially reciprocatingly movable operating member swingably connected with said lever member, resilient means connected to said operating member and to said lever member and forcing the latter into operating position, the direction of movement of said operating member being substantially at a right angle to said clamping arm, said operating member having a portion extending substantially parallel to said extension and comprising an abutment for engaging said extension and limiting movement of said lever member under the influence of said resilient means.

4. A thread gripper for looms comprising a substantially reciprocatingly movable operating member, thread clamp means pivoted to and being swingable on said member, and resilient means connected with said member and with said means and holding the latter in operating position.

5. A thread gripper for looms comprising a substantially reciprocatingly movable operating member, a two-arm lever member pivoted to said operating member and having a thread gripping jaw-like end portion, and having another end portion resiliently connected with said operating member.

6. A thread gripper for looms comprising an operating member, thread gripping clamp means pivoted to said operating member, and a torsion spring connected with said member and said means and resiliently holding the latter in operating position.

7. A thread gripper for looms comprising a substantially reciprocatingly movable operating member having an arm portion, a two-arm lever member pivoted to said operating member and having a thread gripping end portion, and having another end portion resiliently held to said arm portion.

8. A thread gripper for looms comprising an operating member having an arm portion, a two-arm lever member having thread gripping means on one arm thereof and being pivoted to said operating member, and a tension spring interconnecting said arm portion and one arm of said lever member.

9. A thread gripper for looms comprising an operating member, a lever member pivoted to said operating member and having a thread gripping end portion, and resilient means connected with said operating member and engaging said lever member between its pivot point and said end portion.

10. A thread gripper for looms comprising an operating member, thread gripping means, pivot means interconnecting said operating member and said gripping means, and a torsion spring rigidly connected with said pivot means and en-

gaging and holding said gripping means in operating position.

11. A thread gripper for looms comprising a substantially reciprocatingly movable operating member having an arm portion, thread engaging means pivoted to said operating member, and resilient means connected with said member and said means and forcing the latter to said arm portion.

12. A thread gripper mechanism for looms, comprising a two-arm lever member having a thread gripper on one arm thereof, an operating member pivoted at one end to said lever member and extending at substantially right angle thereto and its pivot point forming the fulcrum of said two-arm lever, said operating member having an arm portion extending substantially at a right angle to the longitudinal axis of said operating member and having an abutment portion adapted to abut the other arm of said two-arm lever member, and spring means interconnecting said arm portion and said other arm of said lever member and forcing them together until abutment of said abutment portion and said other arm of said two-arm lever is obtained.

13. A thread gripper mechanism for looms, comprising a two-arm lever member having a thread gripper on one of its arms, a substantially reciprocatingly movable operating member pivoted at one end to said lever member and extending at a substantially right angle thereto and its pivot point forming the fulcrum of said two-arm lever member, an arm rigidly connected with said operating member and extending substantially at a right angle thereto and having an abutment portion adapted to abut the other arm of said two-arm lever member, and tension spring means interconnecting the end portions of said arm of said operating member and of said other arm of said lever member and forcing them together until abutment of said abutment portion and of said other arm of said two-arm lever member is obtained, the line of action of said

spring means being substantially parallel to the direction of the reciprocating movement of said operating member.

14. A thread gripper mechanism for looms, comprising a two-arm lever member having at one end a foot portion having a thread engaging surface portion, another two-arm lever member pivoted to said foot portion and having one arm having a surface corresponding in shape to said first portion and being adapted to press the thread to be gripped to said first surface portion, a spur portion projecting from said first two-arm lever member substantially oppositely said foot portion, and a compression spring disposed between said spur portion and the other arm of said other two-arm lever member for resiliently pressing said surface portions together.

15. A thread gripper mechanism as claimed in claim 14, comprising an outside member, said other arm of said other two-arm lever member having a nose portion adapted to engage said outside member and to tip said other two-arm lever member against the action of said compression spring.
